UNITED STATES PATENT OFFICE.

ALBERT A. DAY, OF NEW YORK, N. Y.

EXTENSIBLE METALLIC SCREEN.

No 846,094.

Specification of Letters Patent.

Patented March 5, 1907.

Application filed June 19, 1906. Serial No. 322,483.

To all whom it may concern:

Be it known that I, ALBERT A. DAY, a citizen of the United States, residing at the borough of Brooklyn, in the city of New York, county of Kings, and State of New York, have invented certain new and useful Improvements in Extensible Metallic Screens; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate several forms in which I have contemplated embodying my invention, and said invention is fully disclosed in the following description and claims.

Referring to the said drawings, Figure 1 represents a complete extensible screen embodying my invention. Figs. 2 and 3 are views of the two screen-sections forming the complete screen illustrated in Fig. 1. Fig. 4 represents an elevation of one corner of the complete screen as it would appear if the two screen-sections were in their closed or non-extended positions. Fig. 5 is a section on line 5 5 of Fig. 4. Fig. 6 is an elevation of one corner of one of the screen-sections, which I term the "inner screen-section," shown in Fig. 3. Fig. 7 is a section on line 7 7 of Fig. 6. Fig. 7^a is a section on line 7^a 7^a of Fig. 6. Fig. 8 is an elevation of one corner of what I term the "outer screen-section" shown in Fig. 2. Fig. 9 is a section on line 9 9 of Fig. 8. Fig. 10 is a view similar to Fig. 6 of one corner of an inner screen-section, showing a slightly-modified construction. Fig. 11 is a section on line 11 11 of Fig. 10. Fig. 12 is a view similar to Fig. 8 of a corner of an outer screen-section, showing a slightly-modified construction. Fig. 13 is a section on line 13 13 of Fig. 12. Figs. 14, 15, 16, 17, 18, and 19 are sectional views of slightly-modified forms of my invention, said sections being similar views to Fig. 5. Fig. 20 is a horizontal sectional view of a window casing and screen, showing a further modification of my invention, the screen herein shown being a laterally-extensible vertically-sliding screen. Fig. 21 is a perspective view of the upper portion of the screen shown in Fig. 20. Fig. 22 is a sectional view on line 22 22 of Fig. 21. Fig. 23 is a detail of the central portion of the upper end of a screen similar to that shown in Figs. 20 to 22, inclusive, showing a modified construction for locking the screen-sections in their adjusted positions.

The object of my invention is to simplify and cheapen the cost of manufacture of metallic extensible window-screens, so as to produce an efficient screen at the lowest possible cost and at the same time one which can be extended laterally to fit any ordinary window-opening.

I will first describe the invention as illustrated in Figs. 1 to 8, inclusive, which illustrate one form in which I have contemplated embodying the invention to obtain the results desired. Referring to these figures, the screen comprises two screen-sections having a lateral sliding engagement with each other, and for convenience of reference I term one the "inner screen-section," thereby designating that section which is constructed to slide within the guiding-flanges of the other section, the latter being designated the "outer screen-section." This designation is artificial and for purposes of convenient explanation and has no reference to the location of the section with respect to the window-opening, as the two sections are flat and when in engagement are nearly in the same plane and can be placed in the window-opening with either section on the outer side.

The inner screen-section is indicated by the letter A and is shown detached in Fig. 3 and in detail in Figs. 6 and 7. The screen-section A consists of a rectangular piece of wire gauze or netting 1, upon the lateral edges of which are placed the vertically-disposed frame-bars 2 2, which consist each of a flat piece of sheet metal folded centrally and longitudinally upon itself and inclosing a marginal portion of the wire-gauze, said folded metal-bar being then provided with a longitudinal bead on one side or beads 3 3 (two beads being shown in the figures referred to) formed by indenting the metal of both folds on the outer side of the section and forcing it outward on the inner side, as shown in Fig. 7. This beading of the folded metal strips 2 2 causes the wire-gauze between them to be bent out of a straight line and stretched following the beads 3 3, and thus also securely fastens the marginal portions of the gauze or netting in said frame-bars. Hereafter in using the term "beaded" or "bead" in the specification and claims I wish to be understood as meaning a construction in

which portions of sheet metal are forced outwardly by corresponding indenting on the opposite side.

4 4 represent the top and bottom bars of the screen-section A, which are each formed from a strip of sheet metal folded centrally longitudinally upon itself and inclosing the upper and lower marginal portions of the wire-gauze 1 and also partially inclosing the ends of the vertical bars 2 2, as indicated at 5 in Figs. 6 and 7. The horizontal bars 4 4 are then provided with a longitudinal bead or beads 6 6, extending throughout the length of the bars. In this form of the invention the lateral or vertical bars 2 2 are made slightly shorter than the wire-netting, so that they will only project into the horizontal bars as far as the first bead 6, (see Figs. 6 and 7,) and the beads 3 3 do not extend throughout the length of the bars 2 2, but are stopped far enough from each end to clear the edges of the horizontal bars. The beads 3 3 serve only to hold the wire-netting in the frame-bars 2 2 and stiffen the bars; but the beads 6 6 of the horizontal bars extend throughout the length of the bars and serve an additional purpose in that they assist in guiding the inner and outer screen-sections in their sliding movements, as hereinafter more fully explained, and I therefore term the bead or beads 6 6 of the horizontal frame-bars "guiding-beads," to distinguish them from the beads on the vertical frame-bars.

It will be seen by reference to Figs. 3, 6, 35 and 7 and 7^a that the horizontal and vertical bars of the inner screen-section are firmly united and held together by the interlocking of the wire gauze or netting in the beaded portions thereof, and the wire-gauze is also 40 tightly stretched, so that a sufficiently strong and durable yet extremely light screen-section is formed without the use of rivets or solder or other additional connection of the frame-bars. The dispensing with the use of 45 rivets and solder further assists in reducing the cost of manufacture.

The outer screen-section B (illustrated detached in Fig. 2 and in detail in Figs. 8 and 9) consists of a piece of wire gauze or netting 50 provided with lateral vertical frame-bars 8 8, made exactly like the corresponding bars 2 2 of the other section and provided with a longitudinal bead or beads 9 9, (two beads being shown.) The upper and lower edges 55 of the wire-gauze 7 are provided with horizontal frame-bars 10 10, which are each formed of a sheet of metal of greater width than the sheet used in making the corresponding bars 4 4 of the other section and folded 60 longitudinally and centrally upon itself. The portion adjacent to the fold is then bent over on one side, as shown in Fig. 9 at 11, to form a retaining flange or guide, and the remaining portion is provided with a longitudinal bead or beads 12 12 on the face opposite

to guide 11 and of such size that the groove or grooves 13 13, formed on the side adjacent to the retaining flange or guide 11, will fit and guide the bead or beads, as in Fig. 7 at 6 6, of the inner screen-section. The top and bottom parallel bars 10 10 of the outer screen-section also embrace the end portions of the vertical bars 8 8, as indicated at 14, Figs. 8 and 9.

It will thus be seen that when the screen-sections A and B are constructed as before described the section A can be placed in engagement with the section B, the horizontal bars 4 4 of the inner section fitting within the guides or flanges 11 11 of the outer section 8c and the guiding-beads 6 6 of the inner section fitting and being guided in the grooves 13 13 of the outer section, as shown in Figs. 1, 4, and 5, thus enabling the screen to be extended laterally to fit any ordinary window-opening and forming a cheap, strong and light extensible screen.

In Figs. 10 and 11 I have shown a modification of the inner screen-section A' in which the ends of the vertical bars (here designated 2^a) are extended into the horizontal bars 4^a to the fold of the latter, and in beading the horizontal bars 4^a the ends of the vertical bars are transversely beaded and interlocked therein by means of the beads 6^a 6^a, and this 95 construction has certain advantages in the matter of the rigidity of the corners. It necessarily makes the screen thicker at these points than at intermediate points, and therefore the retaining-flanges of the outside frames must be made to provide more room for the inner frame.

Figs. 12 and 13 are detail views showing the outer screen-section B' also made in the manner just described, the ends of the vertical bars (here designated 8^a) being extended entirely within the horizontal bars 10^a and locked therein by the beads 12^a 12^a, the retaining-flange 11^a being constructed to accommodate the increased thickness of the inner section A' at the corners, previously referred to with respect to Figs. 10 and 11.

In Figs. 14 to 19, inclusive, I have shown several modifications of the horizontal bars, the figures being sectional views similar to Fig. 5.

In Fig. 14 the construction is exactly identical with Fig. 5, except that the retaining-flange 11^b of the horizontal bar 10^b of the outer screen-section (here designated B^b) is 120 long enough to extend to the inner edge of the frame and entirely inclose the frame-bar 4^b of the inner screen A^b.

In Fig. 15 the construction is identical with that shown in Fig. 5, except that the retaining-flange 11^c of the horizontal bar 10^c of the outer frame (here designated B^c) is carried down the back of the horizontal bar 4^c of the inner frame A^c below the first bead, and said retaining-flange 11^c is itself beaded 130

so as to fit into the outer groove on the rear face of bar 4^e.

In Fig. 16 the construction is the same as in Fig. 15, except that the retaining-flange 5 (here designated 11^d) is carried down over the entire rear face of the inner frame-bar 4^d and is beaded to fit into both grooves, as shown.

In Fig. 17 a construction similar to Fig. 5 10 is shown, except that the bars 10^e and 4^e are provided with only a single bead.

Fig. 18 shows a construction similar to that shown in Fig. 17, except that the retaining-flange 11^f is straight, and it is of the 15 same width as the horizontal frame-bars 10^f and 4^f.

Fig. 19 is a view similar to Figs. 17 and 18, except that the retaining-flange 11^g is of the 20 same width as the frame-bars 10^g and 4^g and is also beaded to fit into the groove in the rear of the bar 4^g.

In Figs. 20 to 23, inclusive I have shown my improvements embodied in a screen which is not only laterally adjustable, but 25 may be used as a vertically-sliding screen, if desired. In these figures the inner screen-section is indicated at A^g and the outer screen-section at B^g, said sections being constructed in this instance substantially in accordance 30 with the construction illustrated in Fig. 17—that is, with a single bead and the top and bottom bars of the outer frame-section having the retaining-flanges (here designated 11^h) extending only a short way over the rear 35 faces of said bars, as clearly shown in Fig. 21. The outer side or vertical bar 2^h of the inner screen-section and the outer side bar 8^h of the outer screen-section are each made of nearly double the width of the inner side 40 bars, and the portions thereof adjacent to the fold are bent rearwardly, as at 15 16, and are each beaded inwardly to form an exterior groove 17, (see Figs. 20 and 21,) thus forming 45 guiding grooved flanges which project rearwardly from the outer ends of the screen and perpendicularly thereto. 18 18 represent vertical strips of metal each provided with a central outwardly-projecting bead 19, which are adapted to be secured to the guide-rails 50 20 of the window-casing by tacks or brads and form guides or runners for the guiding-flanges 15 16, as clearly shown in Fig. 20. These strips 18 18 are provided at suitable 55 intervals with holes (not shown) through 55 which the securing tacks or brads may be driven to secure them to the window-casing.

In Figs. 21 and 22 I have shown the outer screen-section B^g having its top horizontal bar 10^h provided with a screw 21, passing 60 therethrough and through a slot 22 in the enclosed bar 4^h of the other section and provided on the rear side of the screen with a nut 23, and the lower horizontal bars are in such case similarly constructed. In fitting 65 this screen to the window-casing so that it

will slide vertically after being once placed in position it is only necessary to attach the strips 18 as before described, place the screen in the window and extend it laterally until the grooves 17 17 engage the beads 19 of said strips, and then screw up the screws 21 21, whereupon the screen is locked against lateral movement and may be raised and lowered and is permanently retained in the window-opening until removed by loosening 75 the screws 21 21.

In Fig. 23 I have illustrated a simpler means of fastening or locking the two frames B^g and A^g in their adjusted positions. In this construction the screws 21, slots 22, and 80 nuts 23 are dispensed with, and after attaching the strips 18 18 the operator places the screen in the window and opens it until the flanges 15 16 engage the strips, when he marks with a sharp instrument a scratch on 85 the inner frame-bars 4^h at the ends of the outer bars 10^h, as indicated at 24, Fig. 23. The screen is then removed from the window, laid on a horizontal surface, and extended until in the same position which the 90 screen-sections occupied in the window, which will be indicated by the scratches or marks 24. The operator then takes a pointed nail or other sharp instrument, such as a center-punch, and punches an indentation 95 in the overlapping portions of the horizontal frame-bars, as indicated at 25 in Fig. 23, thus indenting all the thicknesses of metal of the outer and inner frame at such points and securely locking the screen-sections together. 100 The screen may then be replaced in engagement with strips 18 18 by sliding it down from the top, as is usual with a solid screen.

By means of the constructions shown in Figs. 20 to 23, inclusive, a purchaser of such 105 a screen may use it either as a removable extension-screen, or by attaching the strips 18 18 to the window-casing and adjusting and locking the screen-sections, as heretofore described, the screen may be quickly 110 put in place and used as a permanent vertically-sliding screen.

What I claim, and desire to secure by Letters Patent, is—

1. An extensible metallic screen, comprising 115 an inner screen-section and an outer screen-section, each section having horizontal frame-bars provided with longitudinal guiding beaded portions, for engaging corresponding portions of the other section, the outer portions of the horizontal bars of said outer section only being bent over parallel to the faces of said bars on one side to form retaining-flanges for engaging the horizontal bars of the inner screen-section, substantially 120 as described.

2. An extensible metallic screen comprising 125 an inner and an outer screen-section each composed of a section of screen fabric, vertical bars of sheet metal secured thereto, and hori- 130

1. A horizontal bars, each formed of a strip of sheet metal folded longitudinally upon itself, inclosing a marginal portion of the screen fabric and beaded longitudinally to secure and stretch the fabric and form guiding portions to engage the corresponding portions of the other screen-section, the horizontal bars of the outer screen-section only having the portions adjacent to the fold, bent over and parallel with one side of said bars to form retaining-flanges for the inner screen-section, substantially as described.
2. An extensible metallic screen, comprising an inner and an outer screen-section each composed of a section of screen fabric, vertical bars of sheet metal secured thereto, and horizontal bars, each formed of a strip of sheet metal folded longitudinally upon itself, inclosing a marginal portion of the screen fabric and beaded longitudinally to secure the fabric and form guiding portions to engage the corresponding portions of the other screen-section, the horizontal bars of the outer screen-section only having the portions adjacent to the fold, bent over and parallel with one side of said bars to form retaining-flanges for the inner screen-section, said retaining-flanges being also beaded and engaging the grooved portions in rear of the beaded portions of the inner screen-section, substantially as described.
3. An extensible metallic screen comprising an inner and an outer screen-section each composed of a section of screen fabric, vertical frame-bars formed of sheet metal folded longitudinally, embracing marginal portions of the fabric and beaded longitudinally to points adjacent to the ends to stretch and retain the fabric therein, and horizontal bars also formed of sheet metal folded longitudinally inclosing marginal portions of the fabric and the ends of the vertical bars, and beaded longitudinally to stretch and retain the fabric therein, and form guiding portions thereon, the portions of the horizontal bars of the outer screen-section only, adjacent to the fold, being bent over and parallel to one face of said bars to form retaining-flanges for said inner screen-section, substantially as described.
4. An extensible metallic screen comprising an inner and an outer screen-section each composed of a section of screen fabric, vertical frame-bars formed of sheet metal folded longitudinally, embracing marginal portions of the fabric and beaded longitudinally to points adjacent to the ends to retain the fabric therein, and horizontal bars also formed of sheet metal folded longitudinally inclosing marginal portions of the fabric and the ends of the vertical bars, and beaded longitudinally to retain the fabric therein and form guiding portions thereon, the portions of the horizontal bars of the outer screen-section only, adjacent to the fold, being bent over parallel with one face of said bars and engaging the horizontal bars of the other screen-section, and means for locking the horizontal bars of the two screen-sections together, substantially as described.
5. An extensible metallic screen comprising an inner and an outer screen-section each composed of a section of screen fabric, vertical frame-bars formed of sheet metal folded longitudinally, embracing marginal portions of the fabric and beaded longitudinally to points adjacent to the ends to retain the fabric therein, and horizontal bars also formed of sheet metal folded longitudinally inclosing marginal portions of the fabric and the ends of the vertical bars, and beaded longitudinally to retain the fabric therein and form guiding portions thereon, the portions of the horizontal bars of the outer screen-section only, adjacent to the fold, being bent over
- and parallel to one face of said bars to form retaining-flanges for said inner screen-section, the end portions of the vertical frame-bars inclosed within the horizontal frame-bars, extending beyond the beaded portions of the latter, and being correspondingly and transversely beaded, substantially as described.
6. An extensible metallic screen comprising an inner and an outer screen-section, each comprising a piece of screen fabric, vertical bars secured thereto, and horizontal bars secured thereto and beaded longitudinally to form guiding portions to engage corresponding portions of the other section, the horizontal bars of the outer section only having their outer edges bent over to form retaining-flanges for the inner section, and the outside vertical bar of each section having a portion bent perpendicularly thereto, and provided with a groove for engaging a stationary guide, substantially as described.
7. An extensible metallic screen comprising an inner and an outer screen-section, each comprising a piece of screen fabric, vertical bars secured thereto, and horizontal bars secured thereto and beaded longitudinally to form guiding portions to engage corresponding portions of the other section, the horizontal bars of the outer section only having their outer edges bent over to form retaining-flanges for the inner section, and the outside vertical bar of each section having a portion bent perpendicularly thereto, and provided with a groove for engaging a stationary guide, and means for locking the horizontal bars of the inner and outer screen-sections with respect to each other, substantially as described.
8. An extensible metallic screen comprising an inner screen-section, and an outer screen-section, each composed of a piece of screen fabric, vertical frame-bars secured thereto, one of said bars having a perpendicular portion provided with a guiding-groove for engaging a stationary guide, and horizontal frame-bars each formed of a piece of sheet metal folded longitudinally inclosing a marginal portion of the fabric and beaded longitudinally throughout their length to form guiding portions engaging corresponding portions of the other section, the horizontal bars of the outer screen-section only having guiding-flanges bent over parallel with one face of said bars and engaging the horizontal bars of the other screen-section, and means for locking the horizontal bars of the two screen-sections together, substantially as described.
9. An extensible metallic screen comprising an inner screen-section and an outer screen-section, each composed of a piece of screen fabric, vertical frame-bars, each formed of a piece of sheet metal folded upon itself inclosing marginal portions of the fabric, and beaded longitudinally to retain the fabric therein, one of said vertical bars being

wider than the other, and having a folded portion bent at right angles to the main portion substantially throughout its length, and beaded to provide guiding portions to engage

5 a stationary vertical guide, horizontal frame-bars each formed of a strip of sheet metal folded longitudinally inclosing marginal portions of the fabric, and beaded longitudinally to secure the fabric and form guiding portions

10 to engage the other screen-section, and means

for locking the horizontal bars of said inner and outer screen-sections together, substantially as described.

In testimony whereof I affix my signature in the presence of two witnesses.

ALBERT A. DAY.
